CLAIM

The ornamental design for a hood for fishing rod reel seat as shown and described.

DESCRIPTION

FIG. 1 is a front, right-side, top perspective view of a hood for fishing rod reel seat, showing the new design; FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a cross-sectional view taken along line 8-8 in FIG. 2; and,

FIG. 9 is a cross-sectional view taken along line 9-9 in FIG. 4.
